UNITED STATES PATENT OFFICE

JAMES H. GLEASON, OF WILLOUGHBY, OHIO, ASSIGNOR TO THE GAS MACHINERY COMPANY, OF CLEVELAND, OHIO, A CORPORATION OF OHIO

CLAMPING DEVICE FOR COKE-OVEN DOORS

Application filed July 5, 1927. Serial No. 203,595.

My invention relates to coke-oven door structures, and particularly to the means for clamping the closure-members or doors of the oven chambers, in place.

5 The object of the invention is to provide clamping means which may be readily and quickly operated and which at the same time will effect the clamping in an efficient manner.

10 The said invention consists of means hereinafter fully described and particularly pointed out in the claims.

15 The annexed drawings and the following description set forth in detail certain means for carrying out my invention, the disclosed means, however, constituting but one of the various mechanical forms in which the principle of my invention may be employed.

20 In the annexed drawings:

25 Figure 1 represents a broken front elevation of a portion of a coke-oven, showing a door provided with my improved clamping means.

Figure 2 represents a horizontal section taken upon the planes indicated by lines II—II, Fig. 1, and showing the clamping members in their clamping position.

30 Fig. 3 represents a view similar to that of Fig. 2, showing the clamping members in a partially released position.

Fig. 4 represents a view similar to that of Fig. 2, showing the clamping member in a fully released position.

35 Fig. 5 represents a vertical section taken on the planes indicated by lines V—V, Fig. 2.

In the oven structure to which the illustrated embodiment of my invention is applied, the end of the coke-oven chamber 1, Fig. 2, is provided with a metal frame 2, which is formed with a rectangular seat or contact surface 3, entirely surrounding the oven-chamber opening, as shown in dotted lines in Fig. 1, which is engaged by the inner 45 side of the closure-member 4 to seal such opening, such arrangement being old and well known to those skilled in the art. The frame 2 is secured in place on the oven structure by screws 5 mounted in cross-pieces 6 welded to fixed uprights 7, such screws en-

gaging flanges 8 projecting laterally from the frame, as shown in Fig. 2.

The bottom of the frame is secured by screws 9 mounted in a fixed angle plate 10, Fig. 1.

Secured to the sides of the frame are a plurality of clamping devices 11, of a number such as will effect the required complete contact between the frame and closure.

Each of these devices, Fig. 5, includes a horizontal bracket 12 secured to the frame by means of nuts 13 and stud bolts 14, and which is formed with bifurcations 15. The upper bifurcation 15 is formed with a bearing 16 and the lower one with a bearing 17 coaxial with bearing 16. In these bearings is seated a vertical pin 18 formed with a collar 19 resting upon the upper surface of the bracket, and with an eccentric portion 20 which lies between the bifurcations.

To the upper end of the pin is fixedly secured an arm 21 formed at its outer end with a boss 22 having a vertical circular opening 23 therethrough, Fig. 3. Extending through all of and suitably secured in the openings 23 of the arms 21 which are on one side of the frame and closure-member, is a vertical bar 24, so that all of the arms on such side of the frame are connected and may be actuated simultaneously.

A similar bar is provided 70 for the arms which are on the other side of the frame so that all of these arms are connected and may likewise be actuated simultaneously.

75 Fig. 3 represents a view similar to that of Fig. 2, showing the clamping members in a partially released position.

Fig. 4 represents a view similar to that of Fig. 2, showing the clamping member in a fully released position.

80 Fig. 5 represents a vertical section taken on the planes indicated by lines V—V, Fig. 2.

85 In the oven structure to which the illustrated embodiment of my invention is applied, the end of the coke-oven chamber 1, Fig. 2, is provided with a metal frame 2, which is formed with a rectangular seat or contact surface 3, entirely surrounding the oven-chamber opening, as shown in dotted lines in Fig. 1, which is engaged by the inner

90 side of the closure-member 4 to seal such opening, such arrangement being old and well known to those skilled in the art. The frame 2 is secured in place on the oven structure by screws 5 mounted in cross-pieces 6 welded to fixed uprights 7, such screws en-

95 mounted in a fixed angle plate 10, Fig. 1.

100 Each latch 25 is provided with an adjusting screw 28 and the angular form of the latch permits it to be swung around in front of

the closure-member 4 so as to bring the screw into a position perpendicular to the face of the closure-member, as shown in Fig. 5.

Each side of said member 4 is provided with fixed lugs 29 corresponding in number with the clamping devices 25 and which may be engaged by the screws 28 as will be further described.

The operation of the above-described apparatus is as follows: Assuming that the arms 21 and latches 25 have been swung away from the oven-opening and into the position shown in Fig. 4, thereby giving access to the contact surface 3 at the front of the frame 2, and that the door or closure member 4 has been lifted and placed in contact with said frame preparatory to clamping it in place, the bars 27 are grasped and pulled over so as initially to swing all of the latches 25 in front of the door independently of any movement of the arms 21 or pins 18 or bar 24, as shown in Fig. 3, bringing the screws 28 opposite but not in contact with the lugs 29. The bars 24 are now grasped and pulled over so as to swing the arms 21 into the position shown in Fig. 2 and hence rotate all of the pins 18 and the eccentrics 20. Such action causes the eccentrics to pull the latches 25 inwardly toward the door and cause the screws 28 to engage the lugs 29 and thus clamp the door against the frame.

The said screws are so adjusted that they will engage the lugs with the required pressure to effect the clamping operation with the necessary security, as will be understood.

In order to apply the required force for the clamping operation, one of each of the sets of arms 21 is provided with an end socket 30 into which a lever 31 (shown in dotted lines in Figs. 2 to 4 inclusive) may be inserted for this purpose.

The eccentrics 20 are so positioned on the pins 18 that when the arms are in their clamping positions, such eccentrics will lock the arms and latches against inadvertent displacement, by a toggle action, as will be understood.

What I claim is:

1. A clamping device for coke-oven doors comprising, a door-opening frame; a plurality of brackets secured to said frame, vertically aligned on each side of the latter, and each formed with a bearing; a pin journalled in each bearing and having an eccentric portion; a door clamp journalled on each said eccentric portion; arms adapted to turn said pins, respectively; respective means for simultaneously actuating all of said clamps on the two sides, respectively, of said frame; and separate respective means for simultaneously actuating all of said arms on the two sides, respectively, of said frame.

2. A clamping device for coke-oven doors comprising, a door-opening frame; a plurality of brackets secured to said frame on each

side of the latter and each having a bifurcated portion formed with a bearing in each member of said bifurcated portion; a pin journalled in each pair of bearings and having an eccentric portion disposed between the members of the bifurcated portion; a door clamp journalled on each said eccentric portion; arms adapted to turn said pins, respectively; respective means for simultaneously actuating all of said clamps on the two sides of said frame, respectively; and separate respective means for simultaneously actuating all of said arms on the two sides, respectively, of said frame.

3. A clamping device for coke-oven doors comprising, a door-opening frame; a plurality of members rotatably mounted on said frame on each side of the latter and respectively formed with eccentric portions; a plurality of clamps journalled on said members, respectively; door-tightening means adjustably mounted on said clamps, respectively; a plurality of arms for turning said rotatable members; respective means for simultaneously actuating all of said clamps on the two sides, respectively, of said frame; and separate respective means for simultaneously actuating all of said arms on the two sides, respectively, of said frame.

4. A clamping device for coke-oven doors comprising, a door-opening frame; a plurality of members rotatably mounted on said frame, vertically aligned on each side of the latter, and respectively formed with eccentric portions; a plurality of door clamps journalled on said eccentric portions, respectively; respective means for simultaneously turning all of said rotatable members on the two sides, respectively, of said frame; and respective means for simultaneously actuating all of said clamps on the two sides, respectively, of said frame, said last-mentioned movements being independent of the said movements of said rotatable members.

5. A clamping device for coke-oven doors comprising, a door-opening frame; a plurality of members rotatably mounted on said frame, vertically aligned on each side of the latter, and respectively formed with eccentric portions; a plurality of door clamps journalled on said eccentric portions, respectively; a plurality of arms for turning said rotatable members, respectively; respective means for simultaneously actuating all of said arms on the two sides, respectively, of said frame; and separate respective means for simultaneously actuating all of said clamps on the two sides, respectively, of said frame.

6. A clamping device for coke-oven doors comprising, a bracket formed with a bearing, a pin journalled in said bearing and having an eccentric portion; a door clamp journalled on said eccentric portion; an arm for turning said pin; and a second arm for turning said clamp on the eccentric portion of

said pin to impart to said clamp opening and closing movements independently of its movements by the first-mentioned arm.

7. A clamping device for coke-oven doors comprising, a bracket formed with two separated portions having coaxial respective bearings, a pin journaled in said bearings and having an eccentric portion disposed between the bearings; a door clamp journaled 10 on said eccentric portion; an arm for turning said pin; and an arm for turning said clamp on the eccentric portion of said pin.

8. A clamping device for coke-oven doors comprising, a bracket formed with two separated portions having coaxial respective bearings, a pin journaled in said bearings and having an eccentric portion disposed between the bearings; a clamp journaled on 15 said eccentric portion; door-tightening means 20 adjustably mounted on said clamp; an arm for turning said pin; and an arm for turning said clamp on the eccentric portion of said pin.

Signed by me this 21st day of June, 1927.
25 JAMES H. GLEASON.
